UNITED STATES PATENT OFFICE.

WALLACE B. COSGRAVE, OF NEW YORK, N. Y.

DESIGN FOR AN ELECTRIC-LIGHT SOCKET.

47,241.

Specification for Design.

Patented Apr. 20, 1915.

Application filed January 9, 1915. Serial No. 1,472. Term of patent 7 years.

To all whom it may concern:

Be it known that I, WALLACE B. COSGRAVE, a citizen of the United States, residing at New York city, in the county of New York and State of New York, have invented a new, original, and ornamental Design for an Electric-Light Socket, of which the following is a specification, reference being had to the accompanying drawing, forming part thereof.

Figure 1 is a perspective view of an electric light socket showing the new design, and Fig. 2 is a side view of the socket.

I claim:

The ornamental design for an electric light socket, as shown.

WALLACE B. COSGRAVE.
